F. DOUGLAS,
WOOD PLANING MACHINE.

No. 77,013.

Patented Apr. 21, 1868.

FRANK DOUGLAS, OF NORWICH, CONNECTICUT.

Letters Patent No. 77,013, dated April 21, 1868.

IMPROVEMENT IN WOOD-PLANING MACHINES.

The Schedule referred to in these Letters Patent and making part of the same.

TO ALL WHOM IT MAY CONCERN:

Be it known that I, FRANK DOUGLAS, of Norwich, in the county of New London, and State of Connecticut, have invented a new and improved Wood-Planing Machine; and I do hereby declare that the following is a full, clear, and exact description of the construction and operation of the same, reference being had to the annexed drawings, making a part of this specification, in which—

Figure 1 is a vertical section through the line xx , fig. 2.

Figure 2 is a side elevation, showing the gear and the ends of the feed-rolls.

Figure 3 represents an end view of one of the journal-boxes of the gear-wheels, the outer cap being removed.

The object of this invention is to provide means for rendering the feed-rolls more perfectly self-adjustable to planks, boards, &c., of different thicknesses. In accomplishing this object, the upper rolls are supported in a novel manner, and a new kind of adjustable gear is employed to operate them. A new arrangement is also used for applying adjusting-weights to the upper rolls.

In the drawings, A represents the frame of the machine, and B B' are the lower feed-rolls, fixed in position, and rotating upon journals b b, by power applied in any suitable manner. C C' are the upper feed-rolls, supported upon journals c c' by a yoke, D, pivoted at its centre upon a vertically-sliding standard, E, in such a manner that either of the upper feed-rolls can be raised while the other is depressed, the standard or fulcrum E remaining immovable, or, one of the upper feed-rolls being held immovable as a fulcrum. The other, together with the sliding standard, can be raised or depressed to a considerable extent. The object of this arrangement is that if, in planing, a thin board, F, is run through the machine, and a thick one, G, immediately follows, it will not be necessary to stop the machine and readjust the feed-rolls to let the latter go through, but while the feed-roll C' is resting on the thin board, the thick one will pass under roll C, and the roll will rise to accommodate it, the slide E rising to allow the roll C to ride over the thick board; or, if a thick board precedes, the rolls will adjust themselves to the thin one that follows, in an equally perfect manner.

In order to set the upper rolls at the proper distance from the lower ones, I support the sliding fulcrum or standard E upon a vertical screw-shaft, H, which screws into the standard; and can be rotated by the proper gear, applied to the bevelled gear-wheel h, at its lower extremity. The screw-shaft itself slides up and down through the wheel h, the latter being fixed in position, but is prevented from rotating independently of the bevel-wheel by a spline or feather, i. J is a fixed collar on the shaft I, and K is a ring or loose collar surrounding the shaft, and resting on the collar J. L is a lever, pivoted at l, the short arm of which is attached to the loose ring K, its long arm being connected with another lever, L', as shown in the drawings, the latter bearing an adjustable weight.

I do not intend to confine myself to any particular form and construction of these levers. One alone may be used, or, instead of a lever, any other device or mechanical expedient may be employed, by which the ring K can be connected with an adjustable weight, so that the upper rolls can be made to bear down on the boards that are planing with any degree of force that the attendant may deem advisable to employ. As the boards pass between the rolls, they will lift the upper rolls, raise the slide E and screw-shaft H, and throw the weight of the lever upon the ring K. The ring will thus be able to adjust its position to the thickness of the board that is planing, without at any time ceasing to bear down with the same force upon the upper rolls.

As the upper rolls are frequently changing their position, moving up and down, and assuming different inclinations towards each other, it is necessary to run them by adjustable gearing that will change position also, and accommodate itself to their movements. Such a gearing I have constructed for the special purpose of its application in this connection, although I desire to protect myself in its use as applied to any kind of machinery where adjustable gearing is necessary. It consists of four spur-wheels, one of them, m, being fixed to the end of one of the lower feed-rollers; another, m', being fixed to the same end of the movable feed-roller above; another, n, gearing into the wheel m, and held in connection with it by a movable arm, o, pivoted on the shaft

or journal b ; and another, n^1 , gearing into the wheels m' and n , and held in connection with the wheel m' by a movable arm, o^1 , pivoted to the shaft or journal c . The movable ends of the two arms o and o^1 are connected by the arm o^2 . By this means, the wheels n n^1 can be swung up and down on the arms which hold them, without throwing either of them out of gear with the wheel on the feed-roller with which it is connected. In order to render them more completely self-adjustable to the changing position of the upper feed-rollers, I extend the upper arm, o^1 , beyond the bearing of the wheel n^1 , as seen at o^3 , and I there connect it with still another arm, o^4 , the lower end of which works on a fixed pivot, p . This apparatus holds the gear-wheels in position, while allowing them to move sufficiently to adjust themselves, at all times, to the position of the feed-rollers.

I am aware that adjustable gearing has been made before, in which wheels similar to those shown at n n^1 are employed, in connection with pivoted arms somewhat similar to those shown at o o^1 o^2 .

I do not claim to be the inventor of such device, when unconnected with the regulating-arm o^4 , working in the manner described. In all the gearings of this kind hitherto in use, the journals, n^2 , of the wheels n n^1 have been supported in simple holes in the arms. I provide for them, however, a bearing, r , attached to the arm by screws, t t , and which can be adjusted or removed. When the journals are in their bearings, and the arms are in position, all the bearings of said gearing can be oiled while in motion. I cover the ends of the boxes and journals with a cap, v , fixed to the boxes by screws. In the drawings, I have shown the supports for only one end of the feed-rolls. I support their other end preferably in a hinged or sliding frame, which can be moved away or turned back on its hinges, so as to remove the boxes from the journals c c' , and leave the rolls in the position shown in fig. 1. The rolls can then be readily removed.

Having thus described my invention, what I claim as new, and desire to secure by Letters Patent, is—

1. Supporting the feed-rollers C C' upon a librating beam, D , which itself is supported by a sliding standard, that permits it to be adjusted higher or lower, when constructed to operate substantially as and for the purpose described.
2. The combination, with the sliding standard E , of the screw-shaft H , having the collar, or its equivalent, J , and operating in connection with the ring K , lever L , or its equivalent, and bevel-gear k , all constructed to operate substantially as and for the purpose specified.
3. The pivoted arm o^4 , when applied to the spur-gearing n n^1 , m m' , and operating in connection with said gearing, and with the arms o o^1 o^2 o^3 , constructed to operate substantially as and for the purpose described.
4. The removable bearing r , when used in connection with the arms o o^1 ; in an adjustable gear, substantially as and for the purpose specified.

FRANK DOUGLAS.
